CLAIM

The ornamental design for a handle for an implement, as shown and described.

DESCRIPTION

FIG. 1 is a top, front, right side isometric view of a handle for an implement, showing my new design;

FIG. 2 is a top view of the handle for an implement;

FIG. 3 is a bottom view of the handle for an implement;

FIG. 4 is a right side view of the handle for an implement, the left side view being the mirror image thereof;

FIG. 5 is a rear end view of the handle for an implement;

and,

FIG. 6 is a front end view of the handle for an implement. The broken line structure shown at the front end of the handle is for illustrative purposes only and forms no part of the claimed design.
